Car-Axle Box.

Patented Dec. 15, 1836.

NO PRINTED SPECIFICATION AVAILABLE

August 24, 1915.

SPECIFICATION

105

A careful search has been made this day for the original file or a printed copy of the same, for the purpose of reproducing the said specification to form a part of this book, but at this time nothing can be found from which a reproduction or printed copy can be made.

Finis D. Morris,

Chief of Division E.
